DIABETIC KIT OR THE LIKE

Joseph H. Peters, Sheboygan, Wis.

Application May 10, 1957, Serial No. 46,100

Term of patent 3½ years

(Cl. D83—1)

Fig. 1 is a perspective view taken from the front and top of a diabetic kit or the like showing my new design, the rear being identical with the front;

Fig. 2 is a side elevational view thereof;

Fig. 3 is a perspective view thereof with the outer cover removed, disclosing the cap of the syringe compartment on the right and the broken line representation of a bottle of serum in the compartment on the left; and

Fig. 4 is a left side elevational view of Fig. 3.

The dominant features of my design reside in the full line portions of the drawing.

I claim:

The ornamental design for a diabetic kit or the like, substantially as shown and described.
